UNITED STATES PATENT OFFICE

DAVID PELTON MOORE, OF WASHINGTON, DISTRICT OF COLUMBIA, ASSIGNOR TO H. KOHN-STAMM & COMPANY, OF NEW YORK, N.Y.

LAUNDRY-BAG.

No. 893,934.

Specification of Letters Patent.

Patented July 21, 1908.

Application filed January 4, 1908. Serial No. 409,264.

To all whom it may concern:

Be it known that I, DAVID PELTON MOORE, a citizen of the United States, residing at Washington, in the District of Columbia, have invented certain new and useful Improvements in Laundry-Bags, of which the following is a specification, reference being had therein to the accompanying drawing.

10 My present invention relates to improvements in laundry bags, the main object, being the provision of a laundry wash bag, in which is adapted to be inserted laundry such as soiled collars, cuffs and small articles, the 15 said bag being provided with a peculiar form of concealed opening, which is quickly manipulated to insert or withdraw the laundry, and which when concealed is practically closed so that the bag may be thrown or 20 tossed about particularly in a washing machine, without the necessity of tying the mouth or causing the contents to be spilled. To this end, I provide a bag having a mouth or opening at one side of the top, a flap of the 25 same size as the body of the bag being secured to the body of the bag upon the mouth's side thereof, and provided with a similar sized mouth or opening in line with but to the other side of the first mentioned opening; and thus this flap conceals and closes the 30 main bag or receptacle's opening.

To more clearly illustrate the invention, attention is invited to the accompanying drawings, in which:—

35 Figure 1 is a view taken from the concealing or closing flap side of the bag, a portion of the flap being cut away to show the main mouth or opening. Fig. 2 is a similar view with a hand in the position it first assumes in 40 opening the bag. Fig. 3 is a similar view showing the two mouths in the position they assume when inserting anything. Fig. 4 is a section on line $x-x$, Fig. 1. Fig. 5 is a section on line $y-y$, Fig. 1, and Fig. 6 is plan 45 view of the supporting clasp.

Referring to the drawings:—The numeral 1 designates the main receptacle or bag which is made of a porous, yet tough material, so that the bag may be tossed about in a washer 50 without injury and so that the water will pass freely therethrough to cleanse the contents, and which consists of the two sheets a and b , forming the rear, and the single sheet c , forming the front of the bag. In the upper left 55 hand corner of the front sheet c , I provide the

main receptacle mouth or opening 2, which is substantially one-half the width of the bag. Secured to the front sheet c , and also to the entire bag, is what I term the closing and concealing flap 3, whose upper edge 4, is secured to the bag to cover and conceal the mouth 2, while its edges d , e and f , are secured to the bag, the upper edge as at 5, being provided with the opening or mouth 6, which is in line but to one side of the mouth 2, these two 65 mouths being of the same length, approximately.

To act as a re-inforcement, and at the same time to provide a means whereby the bag may be hung, I employ the pliable metal 70 blank 6', as clearly shown in Fig. 6, which is formed with the two T-shaped ends 7, connected by the stem 8, of the two ends, this stem being provided with two openings 9 and 9', which when the blank is bent to form 75 the clasp as shown in Figs. 1, 2 and 3, the openings will aline to receive any supporting means, such as a hook or nail. In order to secure the clasp to the upper central portion of the bag, so as to grasp all 80 sheets of the bag, I employ two staples 10, which pass through the ends of the clasp and the bag.

From the foregoing description taken in connection with the drawings, it is evident 85 that I provide a bag especially adapted for a laundry wash bag, in as much as the opening or mouth to the main bag is readily entered, as clearly shown in Figs. 2, and 3, and when the bag is extended, as shown in Fig. 1, the 90 said main mouth or opening is closed and concealed, so that the laundry contained in the bag is not readily spilled.

What I claim, as new, is:—

1. A bag or receptacle made of flexible fabric, and consisting of a main bag having an opening or mouth at the top to one side thereof, and a concealing and closing flap secured to the bag and provided with an opening or mouth substantially the same in size 95 as the opening in the main bag and in the top but to one side of the bag's opening or mouth.

2. A bag or receptacle made of flexible fabric, and consisting of a main bag provided 105 with a mouth substantially one-half the width of the bag at its upper edge to one side of the center of the bag, and a flap secured to the bag to conceal and close said mouth and provided with a mouth adapted to aline 110

with the other mouth when filling or unfilling the bag but to be normally out of line therewith.

3. A bag or receptacle made of flexible fabric, and consisting of a main bag having a mouth at the top to one side thereof, and a concealing and closing flap secured to said bag and provided with an opening out of line with said bag's mouth or opening, said flap's 10 opening being adapted to be alined with the bag's opening when filling or unfilling the bag.

4. A bag or receptacle made of flexible fabric, and consisting of a main bag composed 15 of a series of sheets of fabric, one of which is

provided with a mouth to one side of the bag, a flap secured to said last mentioned sheet to close and conceal the mouth and provided with an opening to one side of but on the same line with the first mentioned 20 mouth, and a supporting and re-inforcing clasp attached to all the sheets of the bag at a point between the two mouths.

In testimony whereof I affix my signature in presence of two witnesses.

DAVID PELTON MOORE.
